ALLEN D. CARDWELL, OF BROOKLYN, NEW YORK.

CONTROLLING SYSTEM FOR RECEIVING APPARATUS.

1,259,835.

Specification of Letters Patent. Patented Mar. 19, 1918.

Application filed November 19, 1913. Serial No. 801,813.

To all whom it may concern:

Be it known that I, ALLEN D. CARDWELL, a citizen of the United States, and resident of New York city, borough of Brooklyn, in the county of Kings and State of New York, have invented certain new and useful Improvements in Controlling Systems for Receiving Apparatus, of which the following is a specification.

- 10 The object of my invention is to provide an electrical controlling system adapted to operate by impulses sent over a main line, whereby the breaks and makes or the reversal of polarity of the impulses on the main line may be utilized in succession in the operation of my improved system, wherein the circuits are made and broken upon the operation of the armature of a line relay.
- 20 By means of my improvements I am enabled, by the use of a relay in a normally closed line, upon a break in such line, to utilize the first make or break of the line, or the first reversal of polarity of the line battery, to cause the operation of an operating-relay, also to prepare a circuit through a second operating-relay, and also to prepare a circuit for a third operating-relay directly upon the interruption of the first line action; upon the second line action the second named operating-relay is energized; upon the third line action the third named operating-relay is energized, and a circuit through a fourth operating-relay is prepared, and directly upon the interruption of said third line action a circuit for a fifth operating-relay is prepared; upon the fourth line action the fourth named operating-relay is energized, and so on for as many operating relays as desired, and then directly upon the interruption of the last line action of a predetermined number of such actions the operation is caused of signaling or other operating devices of the system for the production of the required work, such as the operation of a telegraph typewriter, and the restoration of all the circuits and devices to normal.

In the foregoing statement it will be understood that I may utilize makes and breaks, or reversals of current, in the main line, to effect the operations stated. In the example illustrated in Figures 1 and 2 of the accompanying drawings the main line is adapted to be operated by breaks and makes in the main line, and the operating relays

illustrated in Fig. 1 are intended to operate only upon a long signal on the line, so that the magnets of their corresponding selective devices, the circuits of which are controlled by said operating relays, will not be energized by reason of short signals on the line.

While I have referred to a line signal as a make or a break, it is to be understood that the main line relay armature, in the example illustrated, in Fig. 1, first moves to close certain circuits and partially establish one or more other circuits, and that while the armature is away from such position (after having reached such position in operation) it causes the operation of one of the circuits it established on its preceding engagement of contacts.

My improvements may be established in connection with ordinary telegraph lines, without alteration of the same, other than by providing suitable means for operation of the line relays of my improvements on such lines. It will be understood that any suitable transmitting mechanism may be provided for sending the required signals over the line to operate the line relay of my improved controlling system.

Referring more particularly to the accompanying drawings, Fig. 1 diagrammatically illustrates my improved system:

Fig. 2 is a detail diagrammatic illustration showing a local circuit for controlling contacts 6, 7 and 21;

Fig. 3 is a similar view illustrating a polar relay controlled by the reversal of current in the main line, and

Fig. 4 is a diagrammatic detail illustrating the main line comprising two wires as hereinafter referred to.

The letter *a* indicates a main line, which may comprise a normally closed telegraph line, having a relay *b*, line *a* being shown grounded at *c*. At 1, 2, 3, 4 and 5 are relays, the circuits of which are adapted to be controlled by the armature *b'* of relay *b* which may be in the main line (Fig. 1), or in a local circuit controlled by the armature *a'* of main line relay *a'*, as illustrated in Fig. 2. Said armature is shown connected with one terminal of a local battery *d*, through wire 32, armature *F'* and normally closed contact 31, the opposite terminal of which battery is grounded at *e*. Contact 6 is in the circuit for corresponding terminals of the relays 1, 3, 5, and con-

2

tact 7 is in the circuit for the corresponding terminals of relays 2 and 4, the opposite terminals of which relays are connected to ground f by common return 8. At A, 5 B, C, D are switching relays, adapted to establish circuits in conjunction with relay b successively for the relays 1, 2, 3, 4, 5, and at E, F are relays, the circuits of all of which relays are controlled by armature 10 b' and which relays are adapted to control circuits as hereinafter explained. A wire 9 is connected with contact 6, and includes a variable impedance 10, and is connected with armature D' of relay D, held 15 normally by its spring against the contact 11, which is connected by wire 12 with the armature B' of relay B, which armature normally engages contact 13 connected by wire 14 with relay 1. By this means the 20 circuit for the relay 1, through battery d , is established upon the first break of a series of makes and breaks in main line a , by the closing of armature b' against contact 6. Thereupon, if the break in the main 25 line a be long, relay 1 will operate, according to the example herein described. Contact 7 is connected with wire 15 which includes a variable impedance 16, which wire leads to armature C' of relay C, which 30 armature is held by its spring normally against contact 17 connected by wire 18 with armature A' of relay A. Armature A' is normally out of contact with, but is adapted to engage, a contact 19 connected by wire 35 20 with a terminal of relay 2, but the circuit of said relay is normally broken at 19, notwithstanding that armature b' normally engages contact 7. When the line a is first broken, armature B' is moved by its spring, 40 not only to close the local circuit from the battery through relay 1, but also to close a circuit for shifting magnet A, to cause the latter to close a contact in the circuit of relay 2 at A^2 , 19, as follows: A contact 21, 45 adapted to be engaged by armature b' is connected with wire 22 which connects with armature D' of relay D, which armature is normally in engagement with contact 23 that is connected by wire 24 with armature 50 B' of relay B. Armature B' normally engages contact 25 that is connected by wire 26 with a terminal of relay A, the opposite terminal of which relay is connected through a resistance to ground 27. With 55 the arrangement so far described, when the first break occurs in main line a , and the armature b' of the main line relay engages contacts 6 and 21, the circuit of battery d will be established through relay 1 as before described, and at the same time the circuit for relay A is established from battery d , through armature b' , contact 21, 60 through 22, D^2 , 23, 24, B^2 , 25, 26 and relay A to ground 27. Said relay thereupon attracts its armatures A' and A^2 , and arm-

ture A^2 closes the circuit at 19 for relay 2 to contact 7, from ground f , through 8, 2, 20, 19, A^2 , 18, 17, C^2 , 16 and 15 to 7, while armature A' engages contact 28, establishing a holding circuit for said relay A, which 70 holding circuit includes relay B, but said holding circuit is not energized until armature b' breaks circuit at 21. Upon such break at 21 current will flow from battery d , through 32, armature F' of relay F, contact 31, wire 30, contact 28, wire 29, relay B, wire 26, through relay A and resistance to ground 27. Relay B was not energized when contact was made by armature A' at 28 because of the shunt around relay B comprising circuit from contact 25, connected to one terminal of B, armature B^2 , wire 24, contact 23, armature D^2 , wire 22, contact 21, armature b' , wire 30, armature A' , contact 28, wire 29 to the other terminal of relay B. 80 As soon, however, as the main line a is closed and relay b attracts armature b' , the movement of said armature from contact 21, causes a break in the circuit of relay A at 21, and removes the shunt from relay B, 90 but circuit is maintained through relay A and established through relay B from battery d through 32, F' , 31, 30, A' , 28, 29, B, 26 and A to ground 27, holding the circuit closed for relay 2, at A^2 , 19, and causing magnet B to attract its armatures, thus 95 breaking the circuit of relay 1 at 13 and closing a contact in the circuit for relay 3 by the engagement of armature B' with contact 33, through wire 34 to a terminal 100 of relay 3, while at the same time armature B^2 closes a circuit at contact 35 through wire 36, and relay C to ground 37, but which is still open at 21, b' . When armature b' moves, as stated, from contacts 6, 105 21, the above described actions take place, namely, the breaking of circuit through relay 1, the holding of switching relay armatures A' , A^2 , in operated position and the operation of relay B, which all remain set 110 until final release, as hereinafter explained. As soon as armature b' engages contact 7, current will flow from battery d through armature b' , contact 7, wire 15, armature C^2 , contact 17, wire 18, A^2 , 19 and 20 to 115 relay 2, causing the latter to operate if the signal be long. It may here be stated that if the engagement of armature b' with contacts 6 and 7 be long the relays 1, 2, 3, 4, 5, controlled through said contacts, will be 120 operated, but if such engagement be short the relays 1, 2, 3, 4 or 5 will not be operated on account of the character of said relays and the impedance 10 and 16. Upon the next break in line a , armature b' moving to contacts 6 and 21, completes the circuit for relay 3 from battery d , through b' , 6, 9, D' , 11, 12, B' , 33 and wire 34 to a terminal of relay 3, operating the latter if the break be long, and armature b' includes 130

a circuit from battery d through 21, 22, D^2 , 23, 24, B^2 , 35, 36 and relay C, to ground 37, whereupon armatures C' and C^2 of relay C are operated. Armature C^2 switches the 5 circuit of contact 7 from relay 2 to relay 4 at contact 38, through wire 39, and armature C' prepares a holding circuit for relay C and an operating circuit for relay D at contact 40, through wire 41, D, 42, C and 10 resistance to ground 37. It will be understood that this circuit is not energized until contact at 21 is broken. This is in all respects similar to the corresponding operation of relays A and B.

15 As soon as line a is again closed and armature b' leaves contacts 6 and 21, relay D will be immediately energized, breaking the circuit from contact 6 to relay 3 by the movement of armature D' , and connecting said 20 contact 6 to relay 5 through contact 43 and wire 44. The operation of armature D^2 of relay D also breaks the circuit of contact 21 at 23, and connects contact 21 in circuit with relay E at contact 45, through wire 46, with 25 an effect similar to that described with respect to relays A and B. When armature b' now engages contact 7, circuit for relay 4 is established from battery d , through b' , 7, 15, C^2 , 38 and 39, through relay 4 to ground 8, 30 and said relay will operate if the make in the main line a , armature b' engages contacts 6 and 21, and thereupon a circuit is established through relay 5 from battery 35 d , b' , 6, 9, D^2 , 43, 44 and terminal of relay 5 to ground f , operating said relay if said signal be long. A circuit is also then established for relay E, from battery d , b' , 21, 22, D^2 , 45, 46 and E to ground g . Relay E 40 thereupon attracts its armature E' which is connected with battery d , by wire 49, contact 49 a , armature L' , and wire 32, which armature E' now engages contact 47 that is connected by wire 48 through relay F to wire 45 46, and relay E will be retained energized through the circuit just described after armature b' next breaks contact at 21. As soon as armature b' breaks circuit with contact 21, as stated, relay F will be energized 50 through E to ground g . Armature F' now breaks contact at 31, breaking the holding circuit of relays A, B, C and D, thereby restoring their armatures to normal positions, and closes contact at 31 a . The effect of closing circuit at F' , 31 a will be described hereinafter. The effect of the operation of one or more of the relays 1, 2, 3, 4, 5, which occurs before the operation of armature F' , is as follows: When any of said relays are 55 operated their armatures serve to establish a holding circuit for the corresponding operated relay. Such holding circuit is established upon the breaking of contact 1 b , 2 b , 3 b and the making of contact at 1 c , 2 c , 3 c , as well as at 4 c , 5 c , providing a holding circuit 60 through the corresponding magnet 1 d , 2 d , 3 d , 4 d , or 5 d , and the relay H, from battery d , wire 32, armature L' , normally closed contact 49 a , through the operating winding of relay H, wire 50, through any one of the 70 back contacts 1 b , 2 b , 3 b , and thence through the corresponding armature 1 a , 2 a , 3 a to 51, thence through any one of such armatures that was operated to its corresponding contact 1 c , 2 c , 3 c , and through the corresponding 75 magnet 1 d , 2 d or 3 d , thence through such operated relay and wire 8 to ground f , thereby holding the relay closed and energizing its corresponding electro-magnet 1 a , 2 a or 3 a , and if one of the armatures 4 a or 5 a had been 80 energized its armature closed circuit at 4 c or 5 c , through the corresponding relay 4 or 5. In the latter case relays I and J would also provide circuit as follows: Assume that relay 4 is energized, then the circuit will be 85 from battery d to the relay H as described, to wire 50 and wire 52 directly to armature 4 a , thence through 4 c , magnet 4 d , wire 53, relay I, wire 54, through relay 4 and wire 8 to ground f , thereby holding relay 4 in operated position and energizing magnet 4 d and relay I, the latter for a purpose to be described; and if relay 5 had been operated the circuit would have been established 90 through relay H, as last described with relation to relay H, and wire 50 to 52, thence through armature 5 a , contact 5 c and magnet 5 d , through wire 55, relay J, thence through relay 5 to wire 8 and ground f . The effect of the operation of relay J will be described. 95 When either one of the magnets 1 d , 2 d , 3 d , 4 d or 5 d is operated it will cause the operation of mechanism controlling a type wheel to bring its desired type to the printing position, in the example under consideration. A suitable form of printing telegraph apparatus, adapted to be utilized in conjunction with the magnets 1 d , 2 d , 3 d , 4 d , 5 d , is set forth in my application for improvements in telegraph typewriters, filed April 10, 1915, Serial No. 20386, and wherein magnets corresponding to those lettered M N O P Q R S T, in Fig. 1 of the accompanying drawings, are disclosed adapted to perform the 100 functions hereinafter referred to with respect to said magnets. It will be understood that according to the character of the series of main line signals for the production of any work of the typewriting machine, the operation of one or more of the 105 relays 1, 2, 3, 4 and 5 controls the position of desired type upon the type wheel for printing. Where an operation of the type wheel is not necessary, as for word spacing, the character of signals on line a will be 110 such as not to operate either relays 1, 2, 3, 4 or 5, such as a succession of short signals. Under such conditions, when relay F is energized, as before explained, and its armature F' closes circuit at 31 a , a circuit will 115 120 125 130

be established as follows: from battery d , 32, F', 31^a, through clearing relay L, armature G', normally closed contact 62, wire 63, armature H', normally closed contact 64, wire 65, through release magnet S, spacing magnet R and alining magnet Q to ground f. Relay H will not now be operated. The effect of any operation of release magnet S is to bring the type wheel to normal position if it has been previously shifted to a figure printing position, and the magnet R is for the purpose of advancing the paper carriage one step forward, as between words. Relay L is so timed that, after magnets S and R have performed their functions, the armature L' will be attracted and break the holding circuit of relays E and F, at 49^a, thereby causing their armatures to return to normal. As soon as armature F' breaks contact with 31^a, circuit through relay L and magnets S and R is broken and they are restored to or permitted to resume their normal positions, and then all the parts will be in the positions shown in the drawing. The effect of clearing the line when any one of the magnets M, N, O, P, Q and T, (as well as R and S) have been operated for any purpose will be hereinafter stated.

It will be understood that in accordance with the operation of one or more of the relays 1, 2, 3, 4 or 5, according to a predetermined code or combination of signals, the desired position of the type wheel will be produced. Assuming that any one or more of the relays 1, 2, 3, 4, 5, except 1, 2, 3 in succession, have been energized, closing its armature against its corresponding contact 1^c, 2^c, 3^c, 4^c, 5^c, current will flow from battery d, wire 32, L', 49^a, through the operating winding of relay H, and thence through 50 and the first named relay or relays operated and its corresponding electromagnet to wire 8 and ground f. When relay H now attracts its armature H' it breaks contact at 64 and makes contact at 66, thus providing a circuit from battery d through contact 66, a holding winding of relay H, wire 67, printing magnet T and spacing magnet R, and alining magnet Q, to ground at f, at the time that relay F has been operated and its armature has made contact at 31^a, to then include relay L and armature G' in the circuit with contact 66.

Assuming that relays 1, 2 and 3 have been operated, and their armatures have broken their contacts at 1^b, 2^b and 3^b, respectively, the circuit for relays 1, 2 and 3 will then flow from battery d, 32, L', 49^a, relay H, through the operating winding of relay G, wire 51, to the armatures of relays 1, 2, 3, through their corresponding magnets 1^d, 2^d, 3^d, and through the relays 1, 2, 3, to wire 8 and ground at f. As soon as relay G is energized its armature G' breaks circuit at 62 and makes circuit at 61, so that when relay F has been operated current will then flow from battery d, through wire 32, armature F', contact 31^a, through relay L, armature G', through contact 61, holding winding of relay G to wire 60, thence through armature J', through contact 57 or 58 (according to whether relay 5 has been operated or has not been operated); thence through wire 53 or 59 to armature I' or I² 75 of relay I, (according to whether relay 4 has been operated or not), thence through wires m, n, o, or p, through the respective magnets M, N, O or P, to wire 8 and ground at f, according to the particular combination of the last two impulses affecting relays 4 and 5. Assuming that relays 1, 2, 3, 4, 5 have been operated by a succession of long impulses on a line, it will be understood that as soon as relays 1, 2, 3, have been operated relay G will be energized, as before stated, and its armature G' will make circuit at contact 61 as before described, and then when relay 4 operates, relay I will be energized, attracting its armatures I' and I² and breaking contacts m and p and making contacts n and o, and when 5 now operates relay J will be energized, shifting armature J' from contact 57 to contact 58, so that when relay F becomes 95 energized current will be supplied through wire 32, armature F', contact 31^a, relay L, armature G', contact 61, holding winding of relay G, wire 60, armature J', contact 58, wire 59, armature I², contact o, through magnet O to wire 8 and ground f, and then operating magnet O. As soon as O has performed its function relay L will attract its armature L' and break the holding circuit of E and F at 49^a, as previously described, restoring E and F to normal. Likewise, when armature F' has been restored to normal, relays L, G, H, J, I, 1, 2, 3, 4, 5 and magnets 1^d, 2^d, 3^d, 4^d, 5^d and O will be restored to their normal positions. 110 From the foregoing it will be understood that a succession of impulses, such as to operate the relays A, B, C, D, E and F but not to operate relays 1, 2, 3, 4, and 5, will have the effect of operating magnets S and 115 R, and Q in multiple with R, thereby releasing and spacing as previously described. A succession of signals, such as cause the operation of one or more of relays 1, 2, 3, 4 and 5 (except 1, 2 and 3 in succession) 120 will have the effect of moving the type wheel to a printing position and energizing magnets T, and R and Q in multiple, thereby locking the type wheel in printing position, causing printing, and also spacing of 125 the carriage. Any succession of impulses to effect operation of relays 1, 2 and 3 in succession will effect the operation of magnets M, N, O and P, according to whether relays 4 and 5 have not been energized, or 130

4 has been energized alone without 5, or 5 has been energized without 4, or 4 and 5 have been energized together. Magnets M, N, O and P are, in the example, assumed to control devices as follows: M for line spacing; N for returning the carriage to initial position; O for back spacing of the carriage, and P for shifting the type wheel to figure position. The magnet Q, which 10 always operates in multiple with the word spacing magnet R, is for the purpose of holding the type wheel in rigid alinement, while magnet T is causing printing. Magnet S, when operated, restores the type 15 wheel to its normal position, if it has previously been shifted to figure position. Further detailed description of the operation of the magnets above named will be found in my aforesaid application Serial 20 No. 20386.

In accordance with my improvements, I am enabled to provide a circuit for one of the operating relays instantly to be ready to be operated upon an appropriate signal 25 on the main line, such as a break in such line, and then prepare a circuit for a second operating relay, which will be available the instant the first signal has been succeeded by another on the main line, and also to prepare a circuit for the third signal as soon 30 as the first signal has been succeeded, which is effected as soon as armature b' leaves contact 21; a similar switching is performed for as many impulses as are necessary to 35 perform the required workings, so that upon the final movement of armature b' from contact 21, and while said armature is moving toward its normal position, as upon the closing of the line at the terminations of a 40 series of signals thereon, all the circuits previously established through the medium of such armature are caused to perform their operations, and are restored to normal. It will be observed, therefore, that the time of 45 switching from one such armature stop to another is utilized during the time that armature b' is moving to or is at rest on a contact for an operating relay of its circuit previously established by the preceding 50 signal on the main line, and that a circuit for an operating relay is prepared before the armature b' reaches the corresponding contact 6 or 7, thus saving time in the operation of the system.

55 While I have shown in Fig. 1 a single wire α constituting a main line controlling relay b whose armature closes the circuit at contacts 6, 7 and 21, according to whether the line is opened or closed by a transmitter 60 on the line, it will be readily understood that relay b can be in the form of a polarized relay a^s actuated by a reversal of polarity on the main line for controlling relay b , as illustrated in Fig. 3, or contact 21 can 65 be controlled by a relay α on one wire α' ,

said relay having armatures controlling contacts 6, 7 and 21, and the circuits through contacts 6 and 7 can be controlled at contact y^s by a relay y on another wire y' , said two wires constituting the main line, the 70 flow of current on each such wire being controlled separately, as illustrated in Fig. 4, thus obviating the necessity of having the relays 1, 2, 3, 4 and 5 operating only on long impulses. Hence, by the term main line I 75 mean a line between stations comprising one or more wires, and by the term "devices controlled by signals on the main line," or the term "a controlling relay controlled by signals on the main line," I mean to include 80 a single wire having a single relay for controlling the contacts 6, 7 and 21, or two wires with corresponding relays controlled by signals on each wire, for controlling contact 21 by signals on one wire, and for controlling contacts 6 and 7 by a combination of signals on both wires α' , y' . The relays 1, 2, 3, 4, 5 may be considered to be a group 85 of operating or selective relays, which group has a plurality of sections, comprising a plurality of relays 1, 2, 3, in one section and a plurality of relays 4, 5, in another section; a second group of relays may be considered the relays H and G, relay H being controlled by individual relays of the first group 90 and relay G being controlled by the collective action of one section of relays of the first group, such as the relays 1, 2, 3, and a third group of relays may be considered such as relays E and F, the relays of the 95 third group causing circuits to be utilized as organized by the operation of relays of the first group, which relays of the third group together control the time for actual completion of the circuits through the magnets M N O P Q R S T, the relay F controlling the time during which the circuit is completed through said magnets and also controlling the time during which the circuits of the relays 1, 2, 3, 4, 5 are rendered 100 inoperative after the operation of said magnets.

Having now described my invention what I claim is:—

1. An electric circuit controlling system comprising a plurality of operating relays, normally open circuits therefor, a main line, and devices, including a main line relay for causing the operation of one of said operating relays, preparing the circuit for a second operating relay, and partially preparing a circuit for a third operating relay upon a single operation of the main line relay.

2. An electric circuit controlling system comprising a plurality of operating relays, normally open circuits therefor, a main line, and devices for causing the operation of one of said operating relays, preparing the circuit for a second operating relay, and

partially preparing a circuit for a third operating relay upon a single operation of said devices, said devices serving to break the circuit of the first named operating relay, and partially complete the circuit for the third named operating relay upon the commencement of a second operation of said devices.

3. An electric circuit controlling system comprising a plurality of operating relays, working magnets associated with said relays, normally open circuits therefor, a main line, and devices for causing the operation of one of said operating relays, preparing the circuit for a second operating relay, and partially preparing a circuit for a third operating relay upon an initial operation of said devices, said devices serving to break the circuit of the first named operating relay, and partially complete the circuit for the third named operating relay upon the commencement of a second operation of said devices, said devices closing the circuit through the second named operating relay during the second operation.

4. An electric circuit controlling system comprising a plurality of operating relays, normally open circuits therefor, a main line, devices for causing the operation of one of said operating relays, preparing the circuit for a second operating relay, and partially preparing a circuit for a third operating relay upon an initial operation of said devices, said devices serving to break the circuit of the first named operating relay, and partially complete the circuit for the third named operating relay upon the commencement of a second operation of said devices, said devices closing the circuit through the second named operating relay during the second operation, and electrically operating devices and circuits therefor controlled by the first named devices for holding said operating relays energized, and for restoring the operated relays, and devices to normal upon the termination of the final of a succession of operations of said first named devices.

5. An electric circuit controlling system comprising a plurality of operating relays, normally open circuits therefor, a main line, devices for causing the operation of one of said operating relays, preparing the circuit for a second operating relay, and partially preparing a circuit for a third operating relay upon an initial operation of said devices, said devices serving to break the circuit of the first named operating relay, and partially complete the circuit for the third named operating relay upon the commencement of a second operation, said devices closing the circuit through the second named operating relay during the second named operation,

and electrically operating devices and circuits therefor controlled by the first named devices for holding said operating relays energized, and for causing the breaking of all circuits of the system that are controlled by signals on the main line upon the termination of the final of a succession of signals on the main line.

6. An electric circuit controlling system comprising a plurality of operating relays, one of said relays having a circuit normally ready for closing, the other of said relays having normally open unprepared circuits, a main line, and devices for causing the immediate operation of the first named relay upon the initial operation of said devices, and the preparation of a circuit for a second operating relay and partial preparation of a circuit for a third operating relay upon said operation of said devices.

7. An electric circuit controlling system comprising a plurality of operating relays, one of said relays having a circuit normally ready for closing, the other of said relays having normally open unprepared circuits, a main line, and devices for causing the immediate operation of the first named relay upon the initial operation of said devices and the preparation of a circuit for a second operating relay and partial preparation of a circuit for a third operating relay upon said operation of said devices, said devices breaking the operating circuit of the first named operating relay and partially completing the circuit for the third named operating relay upon the commencement of a second operation of said devices.

8. An electric circuit controlling system comprising a plurality of operating relays, one of said relays having a circuit provided with a normally open contact, normally open unprepared circuits for other operating relays, one of said circuits being provided with a contact associated with the first named contact, and another of said circuits being common to the first named contact, a main line, a controlling relay controlled by signals on the main line, the armature of said relay being adapted to close circuits at said contacts, devices for controlling the circuits of said operating relays, circuits for said devices having a contact to be engaged by said armature and normally out of circuit therewith, said armature being adapted to complete the circuit of the first named operating relay at its said contact upon the production of a signal on the main line and to also close circuit of said devices at their said contact to cause the preparation of the circuit for a second operating relay through the second named contact and partially prepare the circuit for a third operating relay at said first named contact upon the commencement of a second signal

- on the line, said signal causing said armature to complete the circuit of the second named operating relay.
9. An electric circuit controlling system comprising a plurality of operating relays, one of said relays having a circuit provided with a normally open contact, normally open unprepared circuits for other operating relays, one of said circuits being provided with a contact associated with the first named contact, and another of said circuits being connected to the first named contact, a main line, a controlling relay controlled by signals on the main line, the armature of said relay being adapted to close circuits at said contacts, devices for controlling the circuits of said operating relays, circuits for said devices having a contact to be engaged by said armature and normally out of circuit therewith, said armature being adapted to complete the circuit of the first named operating relay at its said contact upon the production of a signal on the main line and to close circuit of said devices at their said contact to cause the preparation of the circuit for a second operating relay through the second named contact and partially prepare the circuit for a third operating relay at said first named contact upon the commencement of a second signal on the line, said signal causing said armature to complete the circuit of the second named operating relay, and electrically operating devices and circuits therefor controlled by the first named devices for holding said operating relays energized and for restoring the operated relays and devices to normal upon the termination of the final of a succession of signals on the main line.
10. An electric circuit controlling system comprising a plurality of operating relays, one of said relays having a circuit provided with a normally open contact, normally open unprepared circuits for other operating relays, one of said circuits being provided with a contact associated with the first named contact, and another of said circuits being common to the first named contact, a main line, a controlling relay controlled by signals on the main line, the armature of said relay being adapted to close circuits at said contacts, switching relays for controlling the circuits of the operating relays, one of said switching relays having a normally open circuit provided with a contact adapted to be engaged by said armature upon the production of the first signal of a succession of signals on the main line, said switching relay being arranged upon the closing of the said contact of its circuit to close the circuit of a second operating relay to the second named contact, another of said switching relays having a circuit controlled by the first named switching relay adapted to be closed by the first named switching relay but establishing a shunt for the second named switching relay through the contact of its circuit controlled by said armature, the breaking of the circuit at said armature upon the commencement of a second signal on the main line causing the second named switching relay to be operated to close the circuit of a third operating relay to the first named contact, the completion of such movement of the armature closing the circuit therewith at the second named contact for the second named operating relay, and electrically operating devices and circuits therefor controlled by the switching relays for holding said operating relays energized and for restoring the operated relays to normal upon the termination of the final of a succession of signals on the main line.
11. An electric circuit controlling system comprising a plurality of operating relays, one of said relays having a circuit provided with a normally open contact, normally open unprepared circuits for other operating relays, one of said circuits provided with a contact associated with the first named contact, and another of said circuits being common to the first named circuit, a main line, a controlling relay controlled by signals on the main line, the armature of said relay being adapted to close circuits at said contacts, switching relays for controlling the circuits of the operating relays, one of said switching relays having a normally open circuit provided with a contact adapted to be engaged by said armature upon the production of the first signal of a succession of signals on the main line, said switching relay being arranged upon the closing of the said contact of its circuit to close the circuit of a second operating relay to the second named contact, another of said switching relays having a circuit controlled by the first named switching relay adapted to be closed by the first named switching relay but establishing a shunt for the second named switching relay through the contact of its circuit controlled by said armature, the breaking of the circuit at said armature upon the commencement of a second signal on the main line causing the second named switching relay to be operated to close the circuit of a third operating relay to the first named contact, the completion of such movement of the armature closing the circuit therewith at the second named contact for the second named operating relay, and electrically operating devices and circuits therefor controlled by the switching relays for holding said operating relays energized and for restoring the operated relays to normal upon the termination of the final of a succession of signals on the main line.
12. An electric circuit controlling system comprising a plurality of operating relays, one of said relays having a circuit provided with a normally open contact which is common to one or more other operating relays, normally open unprepared circuits for one or more other operating relays and having a

common contact associated with the first named contact, a main line, a controlling relay controlled by signals on the main line, the armature of said relay being adapted to close circuits at said contacts, switching relays for controlling the circuits of the operating relays, normally open circuits for said switching relays having a common contact to be controlled by the armature of the main line relay, the armatures of said switching relays being adapted to control the circuits of corresponding operating relays, and to successively control the circuits of the switching relays, a relay E having a circuit controlled by one of the switching relays and by the main line relay, a relay F having its circuit controlled by the armature of the relay E, and a clearing relay having a normally open circuit controlled by the armature of relay F.

13. An electric circuit controlling system comprising a plurality of operating relays, one of said relays having a circuit provided with a normally open contact which is common to one or more other operating relays, normally open unprepared circuits for one or more other operating relays and having a common contact associated with the first named contact, a main line, a controlling relay 25 controlled by signals on the main line, the armature of said relay being adapted to close circuits at said contacts, switching relays for controlling the circuits of the operating relays, normally open circuits for 30 said switching relays having a common contact to be controlled by the armature of the main line relay, the armatures of said switching relays being adapted to control the circuits of corresponding operating relays 35 and to successively control the circuits of the switching relays, a relay H having a normally open circuit provided with contacts normally closed by the armatures of 40 certain of the operating relays, said armatures being adapted to break such contacts and close the circuit of the holding relay 45 through the corresponding energized operating relay, a relay E having a circuit controlled by one of the switching relays 50 and by the main line relay, a relay F having its circuit controlled by the armature of relay E, and a clearing relay having a normally open circuit controlled by the armature of relay F, the armature of the clearing 55 relay being included in the circuit of relay H to break the circuits of relays E, F and H.

14. An electric circuit controlling system comprising a plurality of operating relays, one of said relays having a circuit provided with a normally open contact which is common to one or more other operating relays, normally open unprepared circuits for one or more other operating relays and having a common contact associated with the first named contact, a main line, a controlling

relay controlled by signals on the main line, the armature of said relay being adapted to close circuits at said contacts, switching relays for controlling the circuits of the operating relays, normally open circuits for 70 said switching relays having a common contact to be controlled by the armature of the main line relay, the armatures of said switching relays being adapted to control the circuits of corresponding operating relays and 75 to successively control the circuits of the switching relays, a relay H having a normally open circuit provided with contacts normally closed by the armatures of certain 80 of the operating relays, said armatures being adapted to break such contacts and close the circuit of the holding relay through the corresponding energized operating relay, the circuit of said relay H being connected with the armatures of other of said operating relays, said relays when energized closing the circuit through the corresponding energized operating relay, a relay E having a circuit controlled by one of the 85 switching relays and by the main line relay, a relay F having its circuit controlled by the armature of relay E, and a clearing relay having a normally open circuit controlled by the armature of relay F, the armature of the clearing relay being included in 90 the circuit of relay H to break the circuits of relays E, F and H. 95

15. An electric circuit controlling system comprising a plurality of operating relays, one of said relays having a circuit provided with a normally open contact which is common to one or more other operating relays, normally open unprepared circuits for one or more other operating relays and having a common contact associated with the first named contact, a main line, a controlling relay controlled by signals on the main line, the armature of said relay being adapted to close circuits at said contacts, switching relays for controlling the circuits of the operating relays, normally open circuits for said switching relays having a common contact to be controlled by the armature of the main line relay, the armatures of said switching relays being adapted to control the circuits of corresponding operating relays and to successively control the circuits of the switching relays, a relay H having a normally open circuit provided with contacts normally closed by the armatures of certain of the operating relays, said armatures being adapted to break such contacts and close the circuit of the relay H through the corresponding energized operating relay, the circuit of relay H being connected with the armatures of other of said operating relays, said relays when energized closing the circuit through the corresponding energized operating relay, the circuit through the last named operating relays each includ- 130

ing a relay, magnets having their circuits controlled respectively by the last named relays, a relay E having a circuit controlled by one of the switching relays and by the 5 main line relay, a relay F having its circuit controlled by the armature of the relay E, and a clearing relay having a normally open circuit controlled by the armature of relay F, the armature of clearing relay L being included in the circuit of relay H to break the 10 circuits of relays E, F and H.

16. An electric circuit controlling system comprising a group of relays having normally open circuits, means to control the 15 circuits of said relays, a relay controlled by any of the first named relays, another relay controlled by the coöperative action of some of the relays of the first named group, such second named relays controlling circuits of 20 magnets, certain of the relays of the first named group controlling contacts for said magnets.

17. A circuit controlling system comprising a group of relays, said group having a 25 plurality of sections comprising each a plurality of relays, magnets controlled by said relays, a second group of relays, one of the relays of the second group being controlled by relays individually of the first group and 30 another relay of the second group being controlled by the collective action of one section of relays of the first named group, and a third group of relays, the relays of the third named group causing circuits to be utilized 35 as organized by the operation of relays of the first named group, relays of the third group together controlling the time before actual completion of the circuits through the magnets controlled by the relays of the 40 first group.

18. A circuit controlling system comprising a group of relays, said group having a 45 plurality of sections comprising each a plurality of relays, magnets controlled by said relays, a second group of relays, one of the relays of the second group being controlled by relays individually of the first group and

another relay of the second group being controlled by the collective action of one section of relays of the first named group, and a 50 third group of relays, the relays of the third named group causing circuits to be utilized as organized by the operation of relays of the first named group, relays of the third group together controlling the time before 55 actual completion of the circuits through the magnets controlled by the relays of the first group, a relay of the third group controlling the time during which the circuit is completed through the magnets controlled 60 by the relays of the first group.

19. A circuit controlling system comprising a group of relays, said group having a plurality of sections comprising each a plurality of relays, magnets controlled by said 65 relays, a second group of relays, one of the relays of the second group being controlled by relays individually of the first group and another relay of the second group being controlled by the collective action of one section 70 of relays of the first named group, and a third group of relays, the relays of the third named group causing circuits to be utilized as organized by the operation of relays of the first named group, relays of the third 75 group together controlling the time before actual completion of the circuits through the magnets controlled by the relays of the first group, a relay of the third group controlling the time during which the circuit is completed 80 through the magnets controlled by the relays of the first group, said relay of the third group controlling the time during which the circuits of the relays of the first group are rendered inoperative after 85 the operation of the magnets controlled by the relays of the first group.

Signed at New York city, in the county of New York, and State of New York, this 18th day of November A. D. 1913.

ALLEN D. CARDWELL.
